UNITED STATES PATENT OFFICE.

JOSEPH CONLEY, OF ANADARKO, OKLAHOMA.

INCINERATOR.

1,272,383.

Specification of Letters Patent. Patented July 16, 1918.

Application filed October 27, 1917. Serial No. 198,810.

To all whom it may concern:

Be it known that I, JOSEPH CONLEY, a citizen of the United States, residing at Anadarko, in the county of Caddo and State of Oklahoma, have invented certain new and useful Improvements in Incinerators, of which the following is a specification.

This invention relates to certain new and useful improvements in latrine incinerators and the object of my invention is to provide a device of this character which is simple and substantial in construction, capable of being quickly placed in operation and easily moved from one place to another and at the same time having the highest efficiency in operation.

With these and other objects in view my invention consists in certain constructions, combinations and arrangements of parts the preferred form of which will be first described in connection with the accompanying drawings and then the invention particularly pointed out in the appended claims.

Referring to the drawings wherein the same part is designated by the same reference numeral wherever it occurs,

Figure 1 is a vertical section taken on line 1—1 of Fig. 2 and looking in the direction of the arrow.

Fig. 2 is a similar section taken at right angles to Fig. 1 on line 2—2 of Fig. 1.

Fig. 3 is a horizontal section taken on line 3—3 of Fig. 1, and

Fig. 4 is a vertical sectional view of a modified form of my invention.

The latrine is formed with a front wall 5, side walls 6, 6, a rear wall 7, a top wall 8 and a bottom wall 9.

The top 8 is provided with the openings 10 over which are removably placed the seats 11 provided with the covers 12. It is preferable to make these seats of wood and have them removable so that they will not be injured when the latrine is burned out, during which operation the openings 10 may be closed by metallic covers, such as shown in my prior Patent No. 926,100, granted June 29, 1909.

Located directly below each pair of seat openings is a pan 13, each pan being pivotally mounted on the side walls 6 by means of trunnions 14 provided with heads 15 adapted to seat in open journal plates 16, extending from the interior of the sides.

In order to protect these bearings and to hold the trunnions therein I secure holding plates 17 to the sides of the casing by rivets 18. I also provide the ends of the trunnions 18 with squared openings 19 which may be engaged by a wrench 20 shown in dotted lines in Fig. 2 for the purpose of turning the pans, the sides of the casing being provided with openings 21 in line with the openings 19, said openings 21 being provided with a cover 22 pivoted on the rivet 18.

23 designates a chamber adjacent the end wall 7, said chamber at its upper end terminating in a stack 24. In the lower portion 70 of the chamber there is a grate 25 to which fuel may be fed through the fire door 26. In the form of my invention shown in Figs. 1, 2 and 3, the main chamber of the latrine is connected with the chamber 23 by the 75 openings 27 and 28 which are controlled by dampers 29.

Located in the front portion of the bottom wall 9 of the latrine is a grate 30, and 31 is the fire door for said grate and is located in the front wall 5 of the latrine.

Extending under the entire bottom 9 of the latrine and the chamber 23 is a pan 32. 33 is a partition in the pan formed with an opening 34 controlled by a damper 35, the 85 partition 33 being in line with the rear wall 7 of the latrine. The front of the pan extends out beyond the front wall 5 and it is provided with a cover 36 for the extending portion. The back of the pan is provided with an opening 37 controlled by a damper 38.

39 is an opening (shown in Fig. 1) controlled by a damper 40, through which material may be fed to the lower pan 13. 95

In the form of my invention shown in Figs. 1, 2 and 3 it will be noted that there is a single lower pan 13 and a pair of upper pans 13; that the lower pan is located between the fire built on the grates 30 and the end wall 7 with a space between the pan and the end wall and that there is also a space between the bottom of the pan and the bottom wall 9. The upper row of pans are located between the openings 27 and 28 100 with the rear pan contacting with the rear wall and with a space between the edge of the front pan and the front wall 5.

In the form of my device shown in Fig. 4, it will be noted that there are illustrated 110 three pans in both the upper and lower row; that the front pan of the lower row con-

tacts with the front wall 5 while the front pan of the upper row is spaced away from the front wall, and that the rear pan of the lower row is spaced from the rear wall 7, 5 while the rear pan of the upper row contacts with the rear wall 7. The lower row also is located above the top of the fire on the grate 30, and in addition to the openings 27 and 28 opening through the rear wall 7 10 into the chamber 23 there is an opening 41 controlled by a damper 42 located below the lower row of pans and in the rear wall.

The front wall 5 in addition to the fire door opening 31 is also provided with an 15 opening 43 above the lower row of pans, and a second opening 44 above the upper row of pans, said openings being closed by a door 45.

In the form shown in Fig. 4, the pan 32 20 is not provided with a partition as in the form shown in Figs. 1, 2 and 3, but the bottom wall of the chamber 23 is provided with an opening 46 which can be closed by a sliding damper 47.

25 In the operation of the form of my invention shown in Figs. 1, 2 and 3, a fire is kept continuously burning on the grate 25 and the damper 29 of the opening 28 is kept open with the other dampers closed while all gases 30 and vapors accumulating in the main chamber will consequently pass out into the chamber 23 and there be deodorized and sterilized before passing out of the stack. When there is a sufficient accumulation of material in 35 the pans 13 a fire is built on the grate 30. This fire will drive off the moisture from the solids and at the same time evaporate the liquids. The gases and vapors from the upper pans pass down the front portion 40 of the chamber into intimate contact with the fire on the grate 30. The fire will also entirely surround the lower pan 13, while the gases and vapors will then pass into the chamber 23 where their deodorizing and 45 sterilizing will be completed before they pass into the stack. When substantially all the liquid in the pans 13 has been evaporated the wrench 20 is applied to each of the pans, and they are turned over, dumping the solid 50 matter contained in the top pans down. The pans are then left in their inverted position so that the flame from the fire will thoroughly burn them out and sterilize them. Thereafter the damper 35 will be opened 55 and the damper 38 closed, causing the draft for the fire on the grate 25 to pass through the pan 32, thus evaporating any liquid contained therein.

60 The draft through the pan 32 may be either down through the fire on the grate 30, in which case the damper 36 is only slightly opened or directly through the pan 30, in which case the damper is kept wide open. If desired the course of the products 65 of combustion from the fire on the grate 30

may be over the tops of the upper row of pans. This result is produced by opening the damper 29 of the fuel opening 27. If the flue opening 29 is left open the products of combustion can also be permitted to pass 70 over the top of the lower pan 13. It will thus be seen that by the arrangement of dampers and flue openings shown the products of combustion can be caused to pass all 75 around both tiers of pans, thus affording the highest degree of efficiency both in evaporation and sterilization of the material contained therein. The solid matter remaining in the pans is readily burned on the 80 grate 30.

In the form of invention shown in Fig. 4, the operation is similar to that just described for the dampers. As will be noted the openings are so arranged as to cause the products of combustion to flow in any desired direction around both rows of pans. By having the opening between the side of the casing and one row of pans at one end of the incinerator and the corresponding opening between the side of the incinerator and the 85 upper row of pans at the other end of the incinerator, and having the opening of the upper row farthest away from the stack opening in the casing, the products of combustion can be caused to make a circuitous 90 path over and under both rows of pans. The material to be incinerated may be dumped into the pans through the openings 43 and 44.

I realize that considerable variation is 100 possible in the details of construction and arrangement of parts without departing from the spirit of my invention, and I therefore do not intend to limit myself to the specific form shown and described.

Having thus described my invention what I claim as new and desire to secure by Letters Patent is:

1. In a latrine incinerator the combination with a casing provided with grate bars at its lower portion, a plurality of pans pivoted in the sides of the casing, one of the tiers of pans being spaced from one side wall of the casing and the other tier being spaced from the other side of the casing, a stack 115 adjacent the casing, said casing being provided with openings communicating with the stack above and between the tiers of pans, a second grate located below the stack and dampers for controlling the opening 120 from the casing to the stack.

2. In a latrine incinerator the combination with a casing provided with grate bars in its lower portion, a plurality of pans located in the upper portion of the casing and 125 forming a tier, a single pan located in the lower rear portion of the casing, a grate located in the lower forward portion of the casing, said lower pan being spaced from the bottom of the casing and the rear wall there- 130

of, a stack adjacent the casing, said casing being provided with openings communicating with the stack, dampers for controlling said openings, one of said openings being located between the lower pan and the upper tier, and another of said openings being located above the upper tier.

3. In a latrine incinerator the combination with grate bars in its lower portion, a plurality of tiers of pans pivoted in the sides of the casing, a stack adjacent the casing, said casing being provided with openings above and between the tiers of pans communicating with the stack, a second grate located below the stack, dampers for controlling the opening from said casing to said stack, and a pan located under the entire bottom of the casing, the rear wall of the pan being provided with an opening communicating with the portion of the stack below the second grate.

4. In a latrine incinerator, the combination with a casing, of a plurality of tiers of pans disposed within the casing, a lower pan extending underneath the casing, a stack adjacent the casing, said stack having means of communication with the interior of the casing between said tiers of pans and above the upper tier, and also having communication with the lower pan.

5. In a latrine incinerator, the combination with a casing, of a plurality of tiers of pans disposed within the casing, a lower pan

extending underneath the casing, a stack adjacent the casing, said stack having means of communication with the interior of the casing between said tiers of pans and above the upper tier, and also having communication with the lower pan, a grate disposed within the casing above said lower pan, and a grate disposed within the stack above the point of communication of the stack with the lower pan.

6. In a latrine incinerator, the combination with a casing, of a plurality of tiers of pans disposed within the casing, a lower pan extending underneath the casing, a stack adjacent the casing, said stack having means of communication with the interior of the casing between said tiers of pans and above the upper tier, and also having communication with the lower pan, a grate disposed within the casing above said lower pan, a grate disposed within the stack above the point of communication of the stack with the lower pan, said stack having a draft opening below its grate, and dampers for controlling said draft opening and the communication between the stack, the interior of the casing and the lower pan.

In testimony whereof I affix my signature in presence of two witnesses.

JOSEPH CONLEY.
